UNITED STATES PATENT OFFICE

2,469,201

DOOR LATCH

Anders P. Mikkelsen, Pleasantville, N. Y.

Application November 9, 1946, Serial No. 708,952

6 Claims. (Cl. 292—252)

1

This invention relates to a latching device for doors and particularly to French doors or windows and like hinged closures.

The usual hinged doors or windows, such as French doors, are latched by bolting one of the doors to the top and bottom sills of the door casing and latching the other door to the bolted door.

This invention has for its salient object to provide a door or window latch, particularly for French doors or windows, so constructed and arranged that when one of the pair of doors or windows is closed against the other or complementary door, the other will be automatically latched to the door sill or sills. Moreover, the latch is constructed and arranged so that when the last door closed is opened, the other door section will be unlatched.

Further objects of the invention will appear from the following specification taken in connection with the drawings which form a part of this application, and in which

Fig. 1 is a plan view, partly in section, of a pair of French doors or windows with the doors in closed position;

Fig. 2 is a view similar to Fig. 1 but showing one of the doors swung open;

Fig. 3 is a vertical sectional elevation, partly broken away, illustrating the latching mechanism in latching position;

Fig. 4 is a view similar to Fig. 3 but showing the door having the latching mechanism in position to open after the adjacent or complementary door has been opened;

Fig. 5 is an elevational view of one edge of the door and the latching mechanism mounted therein;

Fig. 6 is an enlarged sectional elevation showing a corner of the door with the latching mechanism mounted therein and disposed in latching position; and

Fig. 7 is a view similar to Fig. 6 but showing four balls instead of three incorporated in the latching mechanism.

In the particular form of the invention illustrated in the drawings there is shown a pair of hinged doors or door sections 10 and 11 mounted in a door casing 12 having an upper sill 13 and a lower sill 14. The door sections are hinged at their outer edges, as shown at 15 and 16, and the section 10 is provided with a latch 17 adapted to engage a complementary latching member on the door section 10 and to latch the two sections together in closed position.

The door section 11 has mounted in the upper

2

and lower inner corners thereof, latching mechanism embodying the invention. From the form of the invention shown, this latching mechanism comprises a casing having plates 20 and 21 disposed at right angles to each other and connected by an arcuate tube 22 open at its ends, as shown at 23 and 24. The open ends of the tubes are mounted in openings 25 and 26 formed in the plates 20 and 21.

10 The open ends 23 and 24 of the tube are slightly reduced in diameter and in each tube there are mounted a plurality of balls 30 having a diameter such that the balls can move freely in the tube 22 and can project partially through the openings 25 and 26 but cannot pass through these openings. In Fig. 6 three balls 30 are illustrated and in Fig. 7 four balls are shown. The number of balls is not material but there should preferably be provided three or more.

15 As shown particularly in Figs. 3 and 4, the upper and lower sills 13 and 14 have formed therein arcuate recesses or seats 31 and 32 adapted to receive the end ball at the upper and lower corners of the door section 11.

20 When the door section 10 is closed on the door section 11, the inner edge 33 of the door section 10 will engage the balls 30A and 30B, thus forcing these balls into the tube 22 and forcing the balls 30C and 30D at the other ends of the tubes partially through the other ends of the tubes and into the depressions 31 and 32 in the upper sill 13 and the lower sill 14.

25 As long as the door section 10 is closed, the balls will be held in this position. However, 30 when this section of the door is opened, the section 11 can be opened and the balls will be forced through the ends of the tube disposed in the edge 35 of the door section 11.

30 From the foregoing specification it will be seen that the usual operation of bolting the door section 11 to the upper and lower door sills is unnecessary with the door latch described and claimed since the closing of the door section 10 after the door section 11 has been closed will

40 automatically latch the door section 11 by forcing the balls in the tube and forcing the end balls 30C and 30D into the seats 31 and 32. It will be clear, moreover, that the latching mechanism described is equally well adapted to doors and windows.

45 Although one specific embodiment of the invention has been particularly shown and described it will be understood that the invention is capable of modification and that changes in the arrangement and in the construction of the various co-

3

operating parts may be made without departing from the spirit or scope of the invention, as expressed in the following claims.

What I claim is:

said latch device comprising an arcuate tube mounted in a corner of one door and having one end opening through the bottom of the corner and another end opening through the inner edge of the door adjacent the inner edge of the adjacent door, a plurality of balls in the tube, said balls being so dimensioned and of such number that when one end ball is pushed substantially flush with one end of the tube by the inner end of the adjacent door the ball at the other end will project partially through the other end of the tube, and a seat for receiving a portion of the ball so pushed out of the end of the tube.

5. In a latch for a door or window casing having a pair of hinged closure members adapted to swing to closed position with their inner edges adjacent and in close proximity to each other, said latch device comprising a tube mounted in a corner of one door and having one end opening through the bottom of the corner and another end opening through the inner edge of the door adjacent the inner edge of the adjacent door and a plurality of balls in said tube having diameters the sum of which exceeds the length of the tube and the end balls in the tube having diameters greater than the diameters of the openings at the ends of the tube whereby the movement of one end ball inwardly of the tube by the inner edge of the adjacent door will partially push outwardly the end ball at the opposite end of the tube, and a seat for receiving said last named ball.

6. In a latch for a door or window casing having a pair of hinged closure members adapted to swing to closed position with their inner edges adjacent and in close proximity to each other, said latch device comprising a tube mounted in a corner of one door and having one end opening through the bottom of the corner and another end opening through the inner edge of the door adjacent the inner edge of the adjacent door, face plates connected to the ends of the tube and arranged at an angle to each other, a plurality of balls in said tube slightly greater in diameter than the diameter of the openings at the ends of the tube, said balls being so dimensioned that when one end ball in the tube is pushed in substantially flush with said end of the tube by the inner edge of the adjacent door the ball at the other end will be partially pushed out of the tube and a seat for receiving a portion of the ball pushed out of the end of the tube.

ANDERS P. MIKKELSEN.
